Inventor

UNITED STATES PATENT OFFICE.

ALFRED L. WHIPPLE, OF LISBON, NORTH DAKOTA.

VARIABLE GEAR FOR BICYCLES.

SPECIFICATION forming part of Letters Patent No. 626,257, dated June 6, 1899.

Application filed March 3, 1898. Serial No. 672,618. (No model.)

To all whom it may concern:

Be it known that I, ALFRED L. WHIPPLE, a citizen of the United States, residing at Lisbon, in the county of Ransom and State of North Dakota, have invented certain new and useful Improvements in Variable Gear for Bicycles; and I do declare the following to be a full, clear, and exact description of the invention, such as will enable others skilled in the art to which it appertains to make and use the same.

My invention relates to improvements in variable-speed gearing for bicycles; and the object is to provide a simple, inexpensive, effective, and durable device for this purpose.

To this end the invention consists in the construction, combination, and arrangement of the several parts of the device, as will be hereinafter fully described and claimed.

The accompanying drawings show my invention in the best form now known to me; but many changes in the details might be made within the skill of a good mechanic without departing from the spirit of my invention as set forth in the claim at the end of this specification.

The same reference characters indicate the same parts of the invention.

Figure 1 is a rear elevation of a bicycle embodying my invention. Fig. 2 is a horizontal section of the same. Fig. 3 is a side elevation, partly in section. Fig. 4 is a detail section of the device for locking the clutch-levers. Figs. 5 and 6 are detail views of the clutches, and Fig. 7 is an enlarged detail view showing the reversely-beveled faces of the sprocket-wheels 13 and 15.

1 denotes the seat-post tube or mast; 2', the back forks; 3, the crank-shaft hanger; 4 4', the backstays, and 5 the rear axle.

6 represents the rear hub, to which the rear wheel is fixed in the usual manner, and it is formed with an annular series of parallel grooves 7 7 to receive the clutch-bars 8 8.

45 The outer ends of these bars each terminate in a toe 9, and 10 12 denote V-shaped collars encompassing said clutch-bars and permanently fixed to them, so that when said collars are moved laterally the bars will slide longitudinally in the grooves in the hub.

13 denotes a small sprocket-wheel loosely journaled on the left-hand end of the rear

axle between the rear brace 4 and fork 2, and the contiguous end of the hub and its inner face are formed with an annular series of 55 clutch-lugs, (not shown,) which are adapted to engage the contiguous toes 9 9 on that end of the clutch-bars 8 8, so as to lock said sprocket-wheel to the hub.

15 denotes a larger sprocket correspondingly arranged on the right-hand end of the rear axle between the rear brace and fork and the contiguous end of the hub, and its inner face is formed with a concentric series of clutch-lugs 16 16, which are adapted to engage 65 the contiguous toes on that end of the bars 8 8.

17 and 18 denote the clutch-levers, independently fulcrumed on the bolts 19 and 20 on the backstays 4 4', respectively, the lower bifurcated end of the lever 17 terminating in 70 V-shaped jaws 21 21, which encompass the collar 10, and the corresponding end of the lever 18 in similar jaws 22 22, which encompass the collar 12.

The upper ends of the levers 17 and 18 terminate in parallel arms 23 24, semicircular in cross-section and having their parallel plane faces abutting, and both arms are encompassed by a cylindrical cap 25, closed at its upper end. This cap is in turn encompassed 75 80 by a sleeve 26, formed with a solid conical head 27, and 28 denotes a helical spring arranged between the closed end of the cap 25 and the inner face of the head 27.

The conical head 27 is formed with a V- 85 shaped groove 29, which is adapted to engage either of the three V-shaped teeth 31, 32, or 33, fixed in the transverse guard or hood 30, secured to the mast or seat-post tube, so as to retain the levers 17 and 18 in either one of 90 the corresponding positions to which they may be adjusted.

34 represents a handle fixed to and extending rearwardly from the sleeve 26, by means of which said sleeve may be conveniently 95 manipulated.

35 and 36 denote sprocket-wheels on the crank-shaft 37, and 38 represents the endless sprocket-chain, extending from the sprocket-wheel 35 to the rear left-hand sprocket-wheel 100 13, and 39 denotes a similar chain connecting the sprocket-wheels 36 and 15.

As shown in Fig. 1, the levers 17 and 18 are set midway of their throw and are held in this

position by the sleeve 26 engaging the middle tooth 32 in the guard or hood 30, and when the levers are locked in this position the clutch-bars are out of engagement with both 5 of the rear sprocket-wheels and which would be the position of the levers when the rider is coasting, the pedals performing the office of foot-rests. If, however, the rider wishes to climb a hill, he reaches under the seat, grasps 10 the handle 34, presses it down to release the head 27 from the tooth 32, and moves it to the left until the head engages with the tooth 31. This movement throws the clutch-bars 8 into engagement with the large sprocket- 15 wheel 15, and consequently a greater leverage is attained than if the handle were thrown to the right so as to engage the opposite ends of said clutch-bars with the smaller sprocket-wheel 13 and which is the proper position for 20 the clutch-levers when the rider is speeding his machine.

It will be observed that the large and small sprocket-wheels may be fixed on the crank-shaft, while sprocket-wheels of the same diameter may be mounted on the rear axle, or, if preferred, the large and small sprocket-wheels on the axle may be geared to corresponding small and large sprocket-wheels on the axle. 25

Having thus described my invention, what 30 I claim, and desire to secure by Letters Patent, is—

The combination in a bicycle, of the backstays and forks, the seat-post tube and the rear axle with the longitudinally-grooved hub 35 loosely mounted on said axle, the clutch-bars sliding in said grooves, the collars connecting said bars, the sprocket-wheels loosely mounted on said axle and formed with clutch-lugs on their inner faces, the clutch-levers ful- 40 crumed on said backstays, and having their lower ends engaging said collars, and their upper ends terminating in parallel arms, a cap encompassing said arms, a spring-actuated sleeve encompassing said cap, a locking- 45 slot in its head, and a transverse hood fixed to said seat-post tube and encompassing said sleeve, and formed with a series of fixed teeth adapted to engage said locking-slot in said sleeve, substantially as shown and described. 50

In testimony whereof I have hereunto set my hand in presence of two subscribing witnesses.

ALFRED L. WHIPPLE.
